UNITED STATES PATENT OFFICE.

FRANCIS H. RICHARDS, OF HARTFORD, CONNECTICUT, ASSIGNOR, BY MESNE ASSIGNMENTS, TO AMERICAN TYPOGRAPHIC CORPORATION, A CORPORATION OF NEW JERSEY.

MECHANICAL MOVEMENT.

No. 853,191.

Specification of Letters Patent.

Patented May 7, 1907.

Application filed April 19, 1901. Renewed May 25, 1904. Serial No. 209,799.

To all whom it may concern:

Be it known that I, FRANCIS H. RICHARDS, a citizen of the United States, residing at Hartford, in the county of Hartford and State of Connecticut, have invented certain new and useful Improvements in Mechanical Movements, of which the following is a specification.

This invention relates to mechanism for starting the rotation about its axis of a wheel having a continuous orbital movement—such, for instance, as a type-wheel—for continuing such rotation and for stopping the rotation of the wheel at a determinate point in the path of its orbital movement, which mechanism is especially adapted for use in connection with a certain class of key-operative mechanism—such, for instance, as that described in my application Serial No. 41,521, filed December 29th, 1900.

In the drawings accompanying the present specification and which set forth an embodiment of my present improvements, Figure 1 is a plan view of such a mechanism. Fig. 2 is a vertical section of the mechanism, part being shown in elevation. Fig. 3 is a sectional elevation of a portion of the mechanism shown in Fig. 2. Fig. 4 is a plan view exhibiting the relation existing between the intermittently-driven member and its driver during the continuous orbital movement of the former. Fig. 5 is mainly a sectional view drawn upon a somewhat larger scale, setting forth in detail the construction of the latch mechanism embodied in the present invention and showing the relation of the latch or gear-starter thereof, when projected, to the part with which it is designed to co-operate. Fig. 6 is a view similar to Fig. 5, but represents the latch as having been pushed inward and set. Fig. 7 is a view similar to Fig. 6, showing the latch in its normal position, as also the key for releasing it. Fig. 8 is a view similar to Fig. 7, showing the position of the parts immediately prior to the release of the latch, a position occasioned by a slight depression of the key. Fig. 9 is a cross-sectional view on the plane of the line a—a in Fig. 6, looking in the direction of the arrow. Fig. 10 sets forth various views of the fulcrum support embodied in the latch mechanism. Fig. 11 sets forth various views of the escapement embodied therein. Fig. 12 is a

plan view of the intermittently-driven member, showing the co-operative relation of a certain part with means for effecting the shifting of the member. Fig. 13 is a cross-sectional view on the plane of the line 13—13 in Fig. 12, a portion of the carrier being shown in this figure.

Similar characters of reference designate corresponding parts in all figures.

The present invention comprises means for carrying a rotatable wheel in an orbital or closed circuit path, combined with a device for initiating the rotation of such wheel at a given point in the path of its orbital movement, and devices brought into operation by the initiation of such rotary movement where by the latter movement is continued to a given point in the orbit at which point the rotary motion is caused to cease.

The mechanism embraced in the present invention is particularly applicable to power-driven typewriters, a type-wheel driven from the rotating wheel operating at a fixed point in its orbital movement to make an impression. The particular die upon the type-wheel caused to operate is determined by the amount of rotary movement given to the wheel, which in turn is dependent upon the point in the path of orbital movement at which the said wheel is started rotating.

The carrier for supporting the rotatable wheel is of suitable construction, and is adapted, as above stated, to move the same through a closed circuit path, and I find it convenient, and have so represented the carrier in the present drawings, to make the same in the form of a rotary carrier or turret designed for continuous rotation about a fixed axis. The turret, designated in a general way in the present specification and drawings by T, may be mounted for its proper movement in a framework of appropriate form and construction. This framework in the present instance embodies a base-plate 2, which may constitute a part of the main framing of the typewriter mechanism with which the present invention is combined, or it may form a subordinate part of that framework.

As mounted in the present case, a stud 3 is rigidly secured to the framework, about which stud the turret rotates, a convenient device for driving the same consisting of a

driving-shaft 4 extending through the stud, which is made hollow for this purpose and connected at one end with a driver and at the other end with the turret. Suitable means are provided for actuating this driving-shaft, that herein indicated in a conventional way consisting of a pulley 5 adapted to be driven from any convenient source of power and rotating about an extension 3' of the stud, the pulley being connected with the driving-shaft 4 by a collar 6, secured, for instance, by a pin 7 to the latter. Preferably the connection of this pulley with the driving-shaft will not be a rigid one the better to prevent strains from being transmitted to the latter. The connection shown for this purpose consists of a pin 8 extending from the collar 6 into a slot of the driving-pulley having a width substantially the same as that of the pin whereby there may be a slight axial adjusting movement of the pulley permitted. Similarly, the connection of the driving-shaft with the turret may consist of a pin 9 extending from a collar 10 on the driving-shaft and located in a slot 11 in the turret. As thus constructed, the weight of the pulley and connected parts is taken by the collar 10, which bears upon the upper end of the stud 3 while the end thrust of the turret is received on a shoulder 12 of the stud. It is evident from an examination of Fig. 2 that the construction allows a slight endwise play of the parts to take place, by reason of the fact that the pin 9 is not normally in contact with the bottom of the slot 11, thereby obviating their cramping even though the ends of the driving shaft be drawn slightly together when under torsion. The present turret construction embodies heads 13, 13 connected with each other by a sleeve or body portion 14. The driven member is conveniently made in the form of a gear-wheel, and it is designated generally herein by B. It is mounted for rotation upon the turret and for this purpose is provided with a shaft b journaled in the heads 13, 13.

Among the purposes for which the present invention is applicable is that of imparting a rotary movement to a revolving type-wheel whereby an impression device thereon may be brought into the impression-forming point and caused to roll over and make an impression upon the surface of paper or other substance located thereat, and I have indicated by dotted lines and in a general way, therefore, a type-wheel 14' secured to the upper end of the shaft b.

A driver for imparting a rotary movement to the driven member during the continuous orbital movement thereof, at the will of the operator, is conveniently made, in the form of an internal gear, designated generally by C. Normally, this driving member is inoperative to effect the rotary movement of the

driven member, but becomes effective for that purpose upon the initiation of the rotary movement of the latter under the control of the operator, as will be more fully set forth hereafter. That is to say, the gear-wheel B forming the driven member is normally out of engagement with the driving member, but upon the initiation of its rotary movement it is moved into engagement therewith.

As the present mechanism is designed to operate at a considerable velocity, I have provided in order to secure safety from breakage in case the driven member be improperly operated in the starting of it, or if the same does not come into alinement with the teeth of the driven member when moved to a position to engage therewith, a mounting for the teeth constituting the driven member which will permit the same to yield slightly. This construction, as set forth, embodies a spring 15 encircling the shank 16' of each tooth 16 inserted in an opening in a suitable gear-block 17 and exerting a pressure between a shoulder on the tooth and a plug 18 closing the outer end of the tooth opening through a bearing in which the stem of the tooth is adapted to slide. These teeth forming the driving member are arranged concentrically about the axis of rotation of the turret, and it is evident from the construction that when the driven member is shifted to bring the teeth of the same into mesh with the teeth of the driving member the latter may yield somewhat should the alinement be incorrect. A stop 19 at the forward end of each tooth limits its forward movement. This feature is claimed in my copending application referred to in the first paragraph of this description.

While the turret is rotating and the driven member B is inoperative, a recessed portion of the periphery of the latter or a portion from which the teeth are omitted lies adjacent to and out of contact with the teeth of the driving-gear; and it may be here stated that to effect the engagement of the two members the driven member is adapted to be shifted axially. As the driven member is in the present case adapted to have more than one revolution the omission of the teeth from the portion which normally travels adjacent to the driving member is supplied by a toothed segment 20 arranged above the plane of the driving-teeth, but in such a position that when the driven member is shifted axially to effect engagement the segment comes into the plane of the driving member; thus the driven member acts in this position as a complete gear having its full complement of teeth. This segment 20 may be formed, as in the present case, as an integral part of the driven member B, or the teeth may be formed upon a separate piece and attached in position to the latter. Such being the rela-

tion of the parts of the gear wheel B, it may by a partial rotation be brought into engagement with the driving member C. If the turret T, be then rotated, an orbital and rotative movement will be given to the gear wheel and to the members rotated thereby. A proper axial shifting of the gear wheel, which may be communicated while said wheel is being rotated by its longer teeth, will move said wheel to a position where all of its teeth will become engageable with the teeth of the driving member C, in which position the gear wheel may be completely rotated by the driving member C. The gear-wheel B, may, moreover, be made in two parts, one being an ordinary toothed wheel and the other a so-called "mutilated" wheel.

For initiating the rotary movement of the driven member and its shaft, there is provided in the present construction a starting-arm 21 similar to the starting-arm described in Patent No. 401,371, dated April 16, 1889, to which reference may be made for a more particular description of its construction and operation. Suffice it here to say that it is provided with a resetting heel 21', which, in combination with a finger portion 21", operates by a toggling action to reset the gear-starter substantially in the manner set forth in the patent referred to. When the shaft b is started rotating by the engagement of the gear-starter or latch with the starting-arm 21, a shifting device is brought into operation to effect the axial movement of the driven member. This device in the present construction consists of an actuating or cam member 22 rigid with the shaft b and a co-operating member 23, herein shown as consisting of a suitably-formed recessed portion 40 on the under surface of the lower head 13 of the turret. When, therefore, the shaft is started rotating the actuating or cam member 22 rides out of the recess forming the member 23, thereby shifting the shaft into a position in which the driven member is brought into engagement with the teeth of the driving member. For the purpose of retaining the various axially-movable parts in their two positions corresponding to the normal or inoperative position of the driven member and its operative position there is provided in this instance a suitable detent device, which, while exerting sufficient force to retain the parts in their two positions, yet yields to permit their movement under the action of the shifting members. This detent device as herein constructed consists of a spring-finger 24 secured to the upper head 13 of the turret and having its detent or end portion 24' adapted to co-operate with a suitably-formed disk or flange 25 upon the turret shaft. Preferably the co-operating surfaces will be inclined, as shown, which will materially assist in the final positioning of the parts endwise when such endwise movement is commenced.

Assuming that the rotary movement of the shaft b and attached type-wheel has commenced and an impression device on the wheel has operated at the impression-forming point, it then becomes necessary to shift the parts axially in the opposite direction to disengage the driven member. The device provided in the present construction for the purpose consists of a cam-plate 26 conveniently affixed to the gear-block 17 and having an inclined face 26' with which coacts a co-operating or cam arm 27' extending from the shaft b and, as the shaft is forcibly rotated, sliding over the inclined surface and upward thereon, operating thus to carry the shaft 80 and attached parts axially and move the driven member out of engagement with the driver. The final positioning of the parts is assisted by the action of the detent 24', and the parts are caused to assume a definite final position by the cam 22, which seats itself in the recess of the member 23. The movement of the shaft endwise and the action of the detent 24' in effecting the final axial movement may be assured by a fixture located at such a portion of the mechanism as to be under the shaft b when the smooth or toothless portion of the driven member arrives opposite the driving teeth, a device for this purpose being shown in the present instance and consisting of a block 26" secured to the base-plate 2 and having an upwardly-extending portion terminating adjacent to the lower end of the shaft b.

If the mechanical movement is applied to a typewriting-machine, a suitable feed-actuating mechanism for imparting motion to the carriage of the typewriter may consist of a star-wheel 27 journaled in the base-plate 2 in a position in which its arms are adapted to move across the axis of the shaft b. When the shaft is in its raised or inoperative position, the lower end b' is raised above the plane of the star-wheel and the latter is not affected by the continued rotation of the turret. When, however, the shaft has been depressed, the end extends below the upper surface of the star-wheel and during the rotary movement of the turret co-operates with the successive arms of the star-wheel to impart an intermittent rotary movement to that wheel, which may be provided with a pinion 28 serving as a driver for the feed mechanism of the typewriter.

It is evident that the amount of rotary movement imparted to the shaft b and hence to the type-wheel attached thereto, will depend upon the arc distance intervening between the impression point and that at which the rotary movement of the type-wheel is commenced. This distance may be made such as to suffice for an amount of rotary movement of the type-wheel that will result in a particular type or impression device being presented at the impression point when

the type-wheel arrives there. For the purpose of initiating this rotary movement there may be combined with the starting-arm aforesaid a suitable bolt or latch which upon its projection into the path of the arm as the same is swung around by the rotation of the turret effects the rotary movement of the shaft to which the starting-arm is attached in a manner set forth in the previously-mentioned patent. Any suitable mechanism for the purpose may be employed for that particular latch mechanism embodied in the present invention. Proceeding now to a description of this latter latch mechanism, I have shown but one such mechanism located at a point outside of the circle of movement of the shaft *b*, which will effect a definite amount of rotation from this point to the impression point. It is evident, however, that a number of the same may be employed located at different points and resulting in different amounts of rotation of the driven member. If a single latch mechanism is employed it (the supporting frame) may be as shown consisting of a block *M* secured to the base-plate 2 and having an opening 28' in which the latch 29 is located and through which it is adapted to move into a position in which its inner end extends into the path of movement of the starting-arm. The latch 29, whatever its cross-sectional form, is journaled at its forward end in a bearing formed in the present instance in a plug 30 secured in the end of the latch recess, and it is provided with a flange 31 whose forward side forms a shoulder co-operating with the plug 30 to limit the outward movement of the latch. The latch is also provided with two catches set one in advance of the other, and the controlling escapement is similarly provided with two catches arranged to be successively engaged by those of the latch. The catches on one of said parts are so constructed and arranged that one of them will sooner than the other engage its corresponding catch so that when such result happens the one so caught may be disengaged and the latch remain hooked back by the other pair of catches, until these are in due succession also disengaged and the latch projected. That is to say, the latch is provided with a catch 32 arranged forwardly of the catch 33, with which catches are adapted to co-operate corresponding catches 34, 35 upon the escapement *E*.

The forward side of catch 33 is beveled, as likewise the surface of the co-operating escapement catch 34, while the rearward side of the catch 33 on the latch is also preferably beveled or inclined. The escapement *E* is supported by a fulcrum-support *F* provided with opposite and rearwardly-extending side-pieces 36, 36 connected at their forward ends by a cross-piece 37 provided with a pivotal portion 38, which is adapted to fit into a recess 39 formed in the bore of the latch open-

ing. To the rearwardly-extending side-pieces of the fulcrum support the escapement is fulcrumed, ears 40, 40 being provided on the escapement for this purpose. A spring 41 located between and bearing against the flange 31 on the latch and the cross-piece 37 of the fulcrum support exerts a pressure to thrust the latch outward when the latter is released by the actuation of the escapement.

It will be noticed, particularly in Fig. 7, which represents the normal or set position of the latch, that the cross-piece 37 of the fulcrum support is inclined somewhat to the axis of the latch, the pressure of the spring tending, therefore, to swing the fulcrum support about its pivotal connection in the latch opening and raise the escapement, the opening through the fulcrum support to permit the passage of the latch being somewhat enlarged to enable the fulcrum support to assume this relative inclination. In this position (which is the normal set position of the latch) the catch 34 bears against the enlarged portion at the rear of the catch 32 on the latch and swings the escapement about this enlarged portion as a fulcrum to raise and hold upward an operating-key whose stem passes through a suitable bearing, here shown to be formed in an arm 42 attached to and extending from the frame *M*. This key may be provided with the usual marked finger-piece *e*, and when the key is depressed the catch 33 on the latch is released from the catch 35 on the escapement and the latch is projected outward by the actuating spring 41. Supposing, now, that the key remains depressed until after the latch has been pressed inward by the toggling action of the starting-arm, the catch 32 on the latch will engage with the catch 34, holding the latch in this position after the starting-arm has left the latch, and preventing thus the same latch from operating the starting-arm more than once during the rotation of the turret for any one depression of the key. When the key is released by the removal of the finger, catch 35 will be moved into the path of movement of the catch 33 on the latch by the action of the spring 41 in urging the outer end of the fulcrum support upward, releasing soon after the catch 34, which, as above stated, has an inclined surface whereby this action is facilitated. Upon the release of the catches 34 and 32 the latch moves outward to a slight extent, contacting, however, with the catch 35, as shown in Fig. 8, by which the latch is retained in its set position until again actuated by the depression of the key.

Having described my invention, I claim—

1. In a mechanical movement, the combination of a driving member; a rotatable axially shiftable member which by a partial rotation is engaged by the driving member and may be further partially but not completely rotated by said driving member and which

- by being shifted axially of the driving member may be completely rotated by said driving member; means for rotating the rotatable member into engagement with the driving member; and means for shifting the rotatable member axially of the driving member.
2. In a mechanical movement, the combination of a driving member; a rotatable axially shiftable member which by a partial rotation is engaged with the driving member and may be further partially but not completely rotated by said driving member and which by being shifted axially of the driving member may be completely rotated by said driving member; means for rotating the rotatable member into engagement with the driving member; and means for disengaging the rotatable member from the driving member.
3. In a mechanical movement, the combination of a driving member; a rotatable axially shiftable member which by a partial rotation is engaged by the driving member and may be further partially but not completely rotated by said driving member and which by being shifted axially of the driving member may be completely rotated by said driving member; means for rotating the rotatable member into engagement with the driving member; means for shifting the rotatable member axially of the driving member; and means for disengaging the rotatable member from the driving member.
4. In a mechanical movement, the combination of a driving member; a rotatable axially shiftable member which by a partial rotation is engaged with the driving member and may be further partially but not completely rotated by said driving member and which by being shifted axially of the driving member may be completely rotated by said driving member; means for rotating the rotatable member into engagement with the driving member; and co-active cam members operative to shift the rotatable member axially.
5. In a mechanical movement, the combination of a driving member; a rotatable axially shiftable member which by a partial rotation is engaged with the driving member and may be further partially but not completely rotated by said driving member and which by being shifted axially of the driving member may be completely rotated by said driving member; means for rotating the rotatable member into engagement with the driving member; and co-active cam members operative to shift the rotatable member axially and also to angularly position said rotatable member.
6. In a mechanical movement, the combination of a driving member; a rotatable axially shiftable member which by a partial rotation is engaged with the driving member and may be further partially but not completely rotated by said driving member and which by being shifted axially of the driving member may be completely rotated by said driving member; a peripherally beveled disk carried by the rotatable member; and a resilient member having beveled faces co-active with the periphery of the disk, and effective to axially position the rotatable member.
7. In a mechanical movement, the combination of a driving member; a rotatable axially shiftable member which by a partial rotation is engaged with the driving member and may be further partially but not completely rotated by said driving member and which by being shifted axially of the driving member may be completely rotated by said driving member; means for effecting the engagement of the rotatable member to cause its partial rotation by the driving member; co-active cam members operative to shift the rotatable member axially; and a stationary cam member effective to reversely shift the rotatable member axially.
8. In a mechanical movement, the combination of a driving member; a rotatable axially shiftable member which by a partial rotation is engaged by the driving member and may be further partially but not completely rotated by said driving member and which by being shifted axially of the driving member may be completely rotated by said driving member; means for shifting the driving member axially to effect the engagement of the rotatable member with and thereby cause its complete rotation by the driving member; a stationary cam member effective to shift the rotatable member axially and thereby disengage the rotatable member from the driving member; a peripherally beveled disk carried by the rotatable member; and a resilient member having beveled faces co-active with the periphery of the disk and effective to axially position the rotatable member.
9. In a mechanical movement, the combination of two elements having engageable faces; a third element rigidly connected with one of said elements and having a face intermittently engageable with the other one of said elements; means for engaging the engageable face of the third element with the element with which it is engageable; means for engaging the engageable faces of the two first-mentioned elements; and means for disengaging the engageable faces of said elements.
10. In a mechanical movement, the combination of two elements having engageable faces; a third element rigidly connected with one of said elements and having a face intermittently engageable with the other of said elements; means for engaging the engageable face of the third element with the element with which it is engageable; means for engag-

ing the engageable faces of the first-mentioned elements; means for disengaging the engageable faces of said elements; and means for definitely positioning said disengaged elements.

11. In a mechanical movement, the combination of two members having gear teeth and meshable with each other; a third member rigidly connected with one of said members and having a partial set of teeth meshable with the other one of said members and also having between two of said teeth a toothless portion non-contactible with the member which is meshable with the teeth of said third member; means for meshing the teeth of the third member with the member with which they are meshable; means for meshing the two first-mentioned members; and means for unmeshing the teeth of said members.

12. In a mechanical movement, the combination of two members having gear teeth and meshable with each other; a third member rigidly connected with one of said members and having a partial set of teeth meshable with the other one of said members and also having between two of said teeth a toothless portion non-contactible with the member which is meshable with the teeth of said third member; means for meshing the teeth of the third member with the member with which they are meshable; means for meshing the two first-mentioned members; means for unmeshing the teeth of such member; and means for definitely positioning the disengaged members.

13. In a mechanical movement, the combination of a rotatable turret; an orbitally rotatable member mounted on the turret; an equally-toothed wheel; a spur gear-wheel mounted on the orbitally rotatable member and having a segmental portion on which the teeth are shortened axially of said wheel, the latter being axially shiftable to two positions in one of which positions all the teeth of said wheel are engageable with the teeth of the equally-toothed wheel and in the other of which positions only the axially longer teeth of said spur gear-wheel are engageable with the equally-toothed wheel; and means for shifting one of said toothed wheels axially.

14. In a mechanical movement, the combination of a rotatable turret; an orbitally rotatable member mounted on the turret; an equally-toothed wheel; a spur gear-wheel mounted on the orbitally rotatable member and having a segmental portion on which the teeth are shortened axially of said wheel, the latter being axially shiftable to two positions in one of which positions all the teeth of said wheel are engageable with the teeth of the equally-toothed wheel and in the other of which positions only the axially longer teeth of said spur gear-wheel are engageable with the equally-toothed wheel; and co-active cam members operative to shift the rotatable member axially and also to angularly position said rotatable member.

members mounted on the turret and on the orbitally rotatable member respectively and operative to shift one of said wheels axially.

15. In a mechanical movement, the combination of a rotatable turret; an orbitally rotatable member mounted on the turret; an equally-toothed wheel; a spur gear-wheel mounted on the orbitally rotatable member and having a segmental portion on which the teeth are shortened axially of said wheel the latter being axially shiftable to two positions in one of which positions all the teeth of said wheel are engageable with the teeth of the equally-toothed wheel and in the other of which positions only the axially longer teeth of said spur gear-wheel are engageable with the equally-toothed wheel; and a stationary cam member engageable with the orbitally rotatable member and effective to shift one of said wheels axially.

16. In a mechanical movement, the combination of a rotatable turret; an orbitally rotatable member mounted on the turret; an equally-toothed wheel; a spur gear-wheel mounted on an orbitally rotatable member and having a segmental portion on which the teeth are shortened axially of said wheel the latter being axially shiftable to two positions in one of which positions all the teeth of said wheel are engageable with the teeth of the equally-toothed wheel and in the other of which positions only the axially longer teeth of said spur gear-wheel are engageable with the equally-toothed wheel; a peripherally beveled disk carried by the orbitally rotatable member; and a resilient member having beveled faces co-active with the periphery of the disk and effective to axially position the orbitally rotatable member.

17. In a mechanical movement, the combination of a rotatable turret; an orbitally rotatable member mounted on the turret; an equally-toothed wheel; a spur gear-wheel mounted on the orbitally rotatable member and having a segmental portion on which the teeth are shortened axially of said wheel the latter being axially shiftable to two positions in one of which positions all the teeth of said wheel are engageable with the teeth of the equally-toothed wheel and in the other of which positions only the axially longer teeth of said spur gear-wheel are engageable with the equally-toothed wheel; and co-active cam members operative to shift the rotatable member axially and also to angularly position said rotatable member.

18. In a mechanical movement, the combination of a rotatable turret; an axially shiftable member mounted in the turret and carrying a peripherally beveled disk; a resilient member mounted on the turret and having beveled faces co-active with the periphery of the disk and effective to axially position the orbitally rotatable member.

19. In a mechanical movement, the com-

bination of a rotatable turret; an orbitally rotatable and axially shiftable member mounted in said turret and carrying a peripherally beveled disk; a stationary cam engageable with the rotatable and axially shiftable member and effective to axially shift said member; and a resilient member mounted on the turret and having beveled faces co-active with the periphery of the disk and effective to axially position the orbitally rotatable and axially shiftable member.

20. In a mechanical movement, the combination of a rotatable turret; an axially shiftable member mounted in the turret and carrying a peripherally beveled disk; a stationary cam member engageable with the axially shiftable member and effective to axially shift said member; and a resilient member mounted on the turret and having beveled faces co-active with the periphery of the disk and effective to axially position the axially shiftable member.

21. In a mechanical movement, the combination of a rotatable turret; an orbitally rotatable and axially shiftable member mounted on said turret; a stationary cam member engageable with the orbitally rotatable and axially shiftable member and effective to axially shift said member; and co-active cam members mounted on said turret and on the orbitally rotatable and axially shiftable member respectively and operative to axially shift said orbitally rotatable and axially shiftable member.

22. In a mechanical movement, the combination of a rotatable turret; an orbitally rotatable and axially shiftable member mounted on said turret and carrying a peripherally beveled disk; co-active cam members mounted on said turret and on the orbitally rotatable and axially shiftable member respectively and operative to axially shift said orbitally rotatable and axially shiftable member; a stationary cam member engageable with the orbitally rotatable and axially shiftable member and effective to axially shift said member; and a resilient member mounted on the turret and having beveled faces co-active with the periphery of the disk and effective to axially position the orbitally rotatable and axially shiftable member.

23. In a mechanical movement, the combination of a rotatable turret; an orbitally rotatable and axially shiftable member mounted on said turret; driving mechanism engageable with and effective to rotate said member; co-active cam members effective to cause the orbitally rotatable and axially shiftable member to engage with the driving mechanism and to angularly position said orbitally rotatable and axially shiftable member; and a stationary cam member engageable with the orbitally rotatable and axially

shiftable member and effective to shift said member.

24. In a mechanical movement, the combination of a rotatable turret; an orbitally rotatable and axially shiftable member mounted on said turret and carrying a peripherally beveled disk; driving mechanism engageable with and effective to rotate said member; co-active cam members effective to cause the orbitally rotatable and axially shiftable member to engage with the driving mechanism; and a resilient member mounted on the turret and having beveled faces co-active with the periphery of the disk and effective to axially position the orbitally rotatable and axially shiftable member.

25. In a mechanical movement, the combination of a driving member; a rotatable member which by an incipient partial rotation is engaged with the driving member and may be further partially rotated by said driving member and which by being shifted axially of the driving member may be completely rotated by said driving member; selective mechanism for rotating the rotatable member into engagement with the driving member; and means for shifting the rotatable member axially of the driving member.

26. In a mechanical movement, the combination of a driving member; a rotatable member engageable therewith and shiftable axially into a position where it is partially rotatable by said driving member and also shiftable axially into another position in which it is completely rotatable by said driving member; and selective mechanism for effecting the engagement of the rotatable member to cause its rotation by the driving member.

27. In a mechanical movement, the combination of two members having gear teeth and meshable with each other; a third member rigidly connected with one of said members and having a partial set of teeth meshable with the other one of said members and also having between two of said teeth a toothless portion non-contactable with the member which is engageable with the teeth of said third member; selective mechanism for meshing the teeth of the third member with the member with which they are meshable, and means for meshing the two first-mentioned members.

28. The combination, with a carrier, of a rotatably-driven member mounted thereon and provided with a recessed portion; a driving member in juxtaposition to which the said recessed portion is located during the movement of the carrier; and means for shifting the driven member axially to engage the same with the driving member.

29. The combination, with a carrier, of a driven member mounted thereon and consisting of a gear-wheel a portion of whose

teeth is removed; a driving member in juxtaposition to which this recessed portion of the gear-wheel is located during the movement of the carrier; a gear segment located at the 5 side of said recessed portion; and means for moving the driven member axially for engaging the same with the driving member;

30. The combination, with a carrier, of a driven member consisting of a gear-wheel a portion of whose teeth, measured axially of the gear-wheel, is removed; a driving member in juxtaposition to which this recessed portion of the gear-wheel is located during the movement of the carrier; a gear segment located at the side of the recessed portion; and means for moving the gear-wheel axially to engage with the teeth of said segment.

31. The combination, with a rotary carrier of turret, of a driven member consisting of a gear-wheel a portion of whose teeth, measured axially of the gear-wheel, is removed; a driving member in juxtaposition to which this recessed portion of the gear-wheel is located during the movement of the carrier; a gear segment located at the side of the recessed portion; and means for moving the gear-wheel axially to engage with the teeth of said segment.

32. The combination of a carrier; a gear-wheel mounted thereon and adapted to be shifted axially; a driven member; a gear-wheel shifter moving with the carrier and operating to shift the gear-wheel axially in one direction; and means for moving the gear-wheel axially in the opposite direction.

33. The combination of a carrier; a gear-wheel mounted thereon and adapted to be shifted axially, and a gear-wheel shifter consisting of a cam moving with said gear-wheel
40 and a corresponding cam-shaped portion on the carrier and adapted to co-operate with the former cam to move the gear-wheel axially.

34. The combination of a carrier; a gear-wheel mounted thereon and adapted to be shifted axially; a gear-wheel shifter consisting of a cam moving with said gear-wheel and a corresponding cam-shaped portion on the carrier and adapted to co-operate with the former cam to move the gear-wheel axially; and means for moving the gear-wheel axially in the opposite direction.

35. The combination, of a carrier; a gear-wheel mounted thereon and adapted to be shifted axially; a gear-wheel shifter consisting of a cam moving with said gear-wheel and a corresponding cam-shaped portion on the carrier and adapted to co-operate with the former cam to move the gear wheel axially; and means consisting of a fixed cam-faced member and a cam arm, adapted to coact with said member to shift the gear-wheel axially, for moving the gear-wheel axially in the opposite direction.

36. The combination, of a carrier; a gear-wheel mounted thereon and adapted to be shifted axially; a gear-wheel shifter consisting of a cam moving with said gear-wheel and a corresponding cam-shaped portion on the carrier and adapted to co-operate with the former cam to move the gear-wheel axially; and means consisting of a fixed cam-faced member and a cam arm, adapted to coact with said member to shift the gear-wheel axially, for moving the gear-wheel axially in the opposite direction, and means for holding the gear-wheel in its two axial positions and for positioning the gear-wheels in a definite rotational position with respect to the carrier. 65

75

37. In a mechanical movement, the combination of a carrier; a feed actuator; a member mounted on the carrier and shiftable axially to engage the feed actuator; co-active cam members effective to shift said shiftable member; a peripherally beveled disk carried by the axially shiftable member; and a resilient member having beveled faces co-active with the periphery of the disk and effective to axially position the axially shiftable member. 90

38. In a mechanical movement, the combination of a carrier; a feed actuator; and a member mounted on the carrier and shiftable axially to engage the feed actuator.

39. In a mechanical movement, the combination of a carrier; a feed actuator, a member mounted on the carrier and shiftable axially to engage the feed actuator; a peripherally beveled disk carried by the axially shiftable member; and a resilient member having beveled faces co-active with the periphery of the disk and effective to axially position the axially shiftable member. 95 100

position the axially shiftable blocks.

40. A driving element consisting of a gear-block having a continuous peripheral portion with recesses formed therein; teeth provided with stop-shoulders and located in said recesses; and springs inserted in the recesses between the teeth and the gear-block. 105

41. A driving member consisting of a gear-block having a continuous peripheral portion with recesses formed therein; teeth located in said recesses; and resilient members severally interposed between the respective teeth and the peripheral portion of the gear-block and urging the teeth outward from said recesses. 110 115

42. A latch mechanism, comprising in combination, a latch, an escapement provided with two catches, a fulcrum support for the escapement, and a spring for projecting the latch when released and operating to disengage one catch and cause the engagement of the other. 120

43. The combination, of a latch, provided with two catches one in advance of the other, an escapement provided with corresponding catches, a fulcrum support for the escape-

ment, and a spring operating to change the relative angular position of the fulcrum support.

44. The combination, of a frame provided with an opening, a latch located in the opening and provided with two catches, one in advance of the other; a fulcrum-support for the escapement pivoted in the said opening, and a spring operating to change the relative angular position of the fulcrum support.

45. The combination, of a latch, provided with two catches, one in advance of the other, an escapement provided with corresponding catches, a fulcrum support, and a spring for projecting the latch when released and operating to change the relative angular position of the fulcrum support to hold one of the catches of the escapement in a position to engage with the corresponding catch on the latch.

46. The combination of a rotatable turret; a torsionally resilient member disposed axially in line with said turret and connected therewith at one end; and a driving member connected with the other end of the torsionally resilient member.

47. The combination of a turret; a member carried thereby and engageable with a fixed member; a torsionally resilient member disposed axially in line with said turret and connected therewith at one end; and a driving member connected with the other end of the torsionally resilient member.

48. In a mechanical movement, the combination of a driving member, a rotatable axially shiftable member for engagement with the gear teeth of the driving member when partially rotated for further partial but not complete rotation, and for engagement therewith for complete rotation when shifted axially, means for inaugurating the rotation of said member into engagement with the driving member and means for disengaging the same from the driving member.

49. In a mechanical movement, the combination of a carrier, an actuator embodying a gear and a member having a complete gear shiftable axially to mesh with the gear on said actuator, and a segmental gear on a parallel plane and shiftable angularly to mesh with the said gear on said actuator.

50. The combination of an orbitally movable and rotary gear, of a gear adapted to mesh therewith, resilient means to initially revolve said former gear, means to put said gears into mesh, and resilient means to ease the strain incident to inaccuracies in the initial meshing of the gears.

51. In a mechanical movement, the combination of a driving member, a rotatable axially shiftable member, when partially rotated for engagement with the gear teeth of the driving member, for partial but not complete rotation by said driving member, and when shifted axially and its gear teeth continually

meshing with those on the said driving member for complete rotation thereby, means for angularly shifting the rotatably engaged member into engagement with the driving member, means for axially shifting said driving member and effective upon the inauguration of the said rotation, and means for disengaging said member from the driving member.

52. The combination with an axially shiftable shaft, of a gear-wheel fast therewith, means for moving said shaft through an orbital path, a driving gear, means for axially shifting said shaft for bringing the said gear-wheel into mesh with said driving gear, and means for returning said shaft and gear wheel to idle position.

53. The combination with an axially shiftable gear-wheel and means for revolving the same, of means for axially shifting said gear-wheel comprising a cam fast with said gear-wheel and a corresponding cam-shaped portion fast with said revolving means for co-operation with said cam.

54. In a mechanical movement, the combination of a driving member, a rotatable axially shiftable member, which, by a partial rotation is engaged with the driving member and may be further partially but not completely rotated by said driving member and which, by being shifted axially of the driving member, may be completely rotated by said driving member, means for rotating the rotatable member into engagement with the driving member, and means for rotating the rotatable member for disengaging the same from the driving member.

55. The combination with a carrier, of a driven member mounted thereon and consisting of a gear-wheel, a portion of whose teeth is removed, a driving member in juxtaposition to which this recessed portion of the gear-wheel is located during the movement of the carrier, a gear segment located in an axial plane parallel with the said recessed portion, and means for moving the driven member axially for engaging the gear segment with the driving member.

56. In a mechanical movement, the combination with a carrier, of an actuator embodying a gear, a member mounted on said carrier and having a gear wheel axially shiftable to mesh with said actuator gear, and also having a segmental gear shiftable angularly to mesh with said actuator gear.

57. In a mechanical movement, the combination with an actuator having a driving wheel, of a member to be actuated thereby and having a driving wheel shiftable axially into and out of driving relation with said actuator driving wheel and a driving arc on a parallel plane, means for angularly shifting said arc for establishing driving relation between the same and said actuator driving wheel, and means for shifting said axially

shiftable driving wheel for establishing driving relation between the same and said actuating driving wheel.

58. The combination with a revolvable 5 and axially shiftable driving member and means for revolving the same, of means for axially shifting said members and comprising a shifter fast with said member and a co-operative shifter fast with said revolving means.

59. The combination with a driving wheel, 10 of means for revolving the same, and means for axially shifting said driving wheel and

comprising a cam fast with said driving wheel and a co-operative cam fast with said revolving means.

15 60. The combination with a driving wheel, of means for actuating the same, and means for axially shifting said driving wheel and comprising co-operative cams controlled by the said wheel and its actuator respectively. 20
